WITNESS:

Walter R. Lockhart

INVENTOR.

BY Charles Bradley
ATTORNEY.

UNITED STATES PATENT OFFICE.

CHARLES BRADLEY, OF DENVER, COLORADO.

RAILWAY-METAL-TIE APPLIANCE.

1,387,462.

Specification of Letters Patent. Patented Aug. 16, 1921.

Application filed August 25, 1919. Serial No. 319,813.

To all whom it may concern:

Be it known that I, CHARLES BRADLEY, a citizen of the United States, residing in the city and county of Denver, State of Colorado, have invented certain new and useful Improvements in Railway-Metal-Tie Appliances; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

In the drawings like characters indicate like parts.

The object of the invention is to provide a substitute for wooden ties, which may be used with entire safety to rolling stock.

Briefly, the invention comprises a hollow metal tie adapted to receive wooden cushions, upon which the rails rest directly. The tie is provided with tongues which project to engage the base of the rail on both sides. One tongue for each rail is mounted on a plate slidably retained on the tie, means being provided for securing the plate in rail-engaging position.

30 In the drawings:

Figure 1 is a plan view with the middle portion of the tie broken away.

Fig. 2 is a side elevation of the showing in Fig. 1.

35 Fig. 3 is a section taken on the line $a-a$, Fig. 2.

Fig. 4 is a fragmentary view of the bottom of the tie.

Fig. 5 is a plan of the base-engaging 40 tongue used on the inside of one of the rails.

The tie in general is hollow and rectangular in cross section. The side walls 2 are spaced by partitions 3, one of which is located adjacent each end of the tie. Between 45 the walls 3 the tie is provided with an integral top, thereby forming a rectangular space 6 in the middle of the tie. The spaces beyond the partitions 3 are open at the top and ends, and are adapted to receive wooden blocks 7, which form cushions for the rails.

In Fig. 2 the side of the tie at one end is shown broken away directly in front of the block 7, to indicate the position of the latter. The block 7 extends slightly above the tops 55 of the walls 2, where the rails 5 are located, in order that the rails may rest directly upon

the blocks or cushions 7 without engaging the tops of said walls 2.

A slideable plate 8 is positioned above each block 7 and the inner end thereof has an extending tongue which engages the rail-base as indicated at 9. One of the rails is held on its inner side by means of an integral tongue 10. Each plate 8 is retained by means of laterally extending guides 11, around which the edges 12 of the plates 8 are bent in order that said plates 8 may slide upon the tie, but will not have movement vertically from the tie. When the plates 8 are slid into engaging position, they are held against longitudinal movement by means of keepers 4, vertically disposed at the ends of the tie and retained in retaining position by means of key-bolts 24.

The rail opposite from that held by the integral tongue 10 has the inner side of its base retained by means of a slideable tongue 13, whose innermost end is equipped with an upstanding handle piece 14, for manipulating the same. The ends of this tongue 13 extend beyond the handle piece as indicated at 15, and are positioned beneath overhanging ears 16, integral with the tie 2. By this means the tongue 13 is slidably guided by said ears 16. When positioned in rail-engaging relation, the tongue 13 may be retained in said position by means of a bolt 17, passing transversely of the tie and through both of the ears 16.

To prevent slipping of the tie, the bottom 19 thereof is provided with T-shaped means, as indicated in Fig. 4.

It will be seen from the foregoing that when a rail is mounted upon one of the blocks 7 and fitted under the integral tongue 10, that it will be firmly held when the corresponding plate 8 is slid into engaging position. Likewise, when the tongue 13 and the corresponding plate 8 are slid into position and fixed, the other rail will be firmly held. The device by this construction will permit free movement of the rail during contraction and expansion thereof under temperature changes. The wooden cushions 7 may be proportioned to fit the cavities at the ends 105 of the tie and have waterproofing composition applied to the cushions around the walls thereof.

I claim:

1. A rail support, comprising a tie, a tongue on the tie to engage one side of the base of a rail, a slideable plate having a

tongue to engage the other side of the rail base, guides for said slidable plate, said plate extending to the end of the tie, and vertically-disposed means on the end of the tie 5 engaging the end of the plate to retain the plate with its tongue engaging said base.

2. A rail support, comprising a tie, a tongue on the tie to engage one side of the base of a rail, a slidable plate having a 10 tongue to engage the other side of the rail base, guides for said slidable plate, said plate being inclined and extending to the end of the top, and means to retain the plate with its tongue engaging said base.

15 3. In combination, a tie, a rail thereon, a tongue on the tie to engage one side of the base of the rail, a slidable plate inclined downward toward the end of the tie and having a tongue to engage the other side of 20 the base, guides for said slidable plate, said plate extending to the end of the tie, and

vertically-disposed means on the end of the tie engaging the end of the plate to retain the plate with its tongue in engagement with said base, and a wooden cushion positioned 25 in a cavity beneath said rail, upon which said rail is adapted to rest.

4. In combination, a tie, a rail thereon, a tongue on the tie to engage one side of the base of the rail, said tongue being slidably 30 mounted on the tie and slidable into engagement with one side of the base of the rail, means to hold the tongue in engagement with the rail, a slidable plate having a tongue to engage the other side of the rail 35 base, guides for the slidable plate, said plate extending to the end of the tie, and vertically-disposed means on the end of the tie engaging the end of the plate to retain the plate with its tongue in engagement with 40 said base.

CHARLES BRADLEY.
